UNITED STATES PATENT OFFICE.

JAN CEELEN, OF ROTTERDAM, NETHERLANDS, ASSIGNOR TO ROTTERDAMSCHÉ MACHINEFABRIEK "BRAAT," OF ROTTERDAM, NETHERLANDS, A COMPANY OF NETHERLANDS.

DAVIT.

Application filed July 14, 1923. Serial No. 651,641.

To all whom it may concern:

Be it known that I, JAN CEELEN, a subject of the Queen of the Netherlands, residing at Rotterdam, Netherlands, have invented certain new and useful Improvements in Davits, of which the following is a specification.

The present invention relates to a boat davit adapted to automatically swing outwardly when the falls are payed out, and it has for its principal object to design a davit of the above type that is of simple, light and comparatively low construction, reliable in operation and readily swings the boat outboard clear of the ship's side.

The novel davit consists of a standard terminating at its lower end in a curved surface adapted to roll on a trackway inclined downwardly towards the ship's side, the arrangement being so that the davit accomplishes a canting movement after having completed its roll on the trackway. The centre of said canting motion may be located close to the ship's side. Owing to this arrangement the davit top, which initially moves at a relatively small distance from deck, can be swung outwardly a sufficient distance for the boat to completely clear the side of the ship. Arresting stops provided in the centre of canting motion and elsewhere on the davit frame ensure the required stability of the davit when completely swung outboard.

The davit may be operated in a simple manner by means of the boat fall which, in accordance with another feature of this invention, may be passed over a pulley or another suitable guiding means at or near that end of the rolling surface of the standard, which ascends during the luffing motion of the davit. Owing to its tension the fall exerts a certain pressure on the said pulley and thereby maintains the correct relation between the standard and the frame which accommodates it.

The annexed drawing illustrates, by way of example only, an embodiment of the present invention, Figure 1 being an end view, and Figure 2 a side view thereof.

The boat 3 is suspended from blocks 4 and 5, roven through which are the falls 6 and 7 operated by a common winch 8.

A beam 9, which may be of tubular for-

mation, is at either end secured to a standard 10 terminating at its lower end in a 55 foot having a curved rolling surface 11 whereby it is adapted to roll on an outwardly inclined trackway 12 of a frame 13 secured to deck. The centre of curvature of the rolling surface is preferably located 60 in the beam 9, so that during the rolling motion of the standards on the trackways 12 said beam moves through a rectilinear path in parallel relation with the trackways. 65 The foot 11 is provided near its outer end with an idler 14 for guiding the boat fall, its other end being equipped with an anti-friction roller 15 for guiding the foot 11 along a cycloidally curved surface of the frame 13. Roller 15 ensures that during the 70 luffing motion of the davit the foot 11 can only roll and prevents sliding movement thereof. After the foot 11 has completed its roll on the trackway 12 the standard starts to cant with the axis of roller 15 as a 75 centre, and when the standard 10 finally assumes the position indicated in Figure 1 by a chain-line it is arrested by its cross pin 17 abutting against the frame 13, whereby the davit is held in a perfectly stable position. 80

The beam 9 is provided with hooks 18 and 19 which, in the position of the davit as illustrated in Figure 2, project into recesses of the blocks 4 and 5, respectively. 85 These hooks prevent the boat from descending, prior to the outward swing of the davit, when the falls are payed out. As soon, however, as beam 9 has reached a predetermined point of its path, for instance, the point 20, the moments of the forces are so that the blocks 4 and 5 have no longer a tendency to move away from the davit when the latter continues its luffing movement. Beyond 90 said point 20 the hooks may safely release the blocks. When assuming position 71 (Figure 1) the falls act on a long lever arm owing to their being passed over pulleys 14, so that they are never unfavorably loaded. When the boat is being raised the falls must 95 temporarily take up part of the weight of the davit in addition to the weight of the boat, so that the falls and the winch must be dimensioned accordingly.

The boat chocks have not been shown on 100 the drawing. As a matter of course said

chocks must be collapsed or otherwise removed from under the boat before the latter can be swung out.

The drawing neither shows how the frames could be provided with latches for sustaining the standards, for instance vertically below the rolls 15, so long as the boat falls have not yet been properly roven or tightened. These latches or other locking means could suitably be associated with the boat chocks in such a manner as to automatically release the davit when the boat chocks are collapsed. Anyway it is obvious that such locking means may not in the least interfere with the swing of the boat.

The boat falls can be tightened by stretching screws to ensure that the standards properly move in their frames and no jamming can occur.

20 As the standards are guided in a simple manner in open frames it is practically impossible for their proper operation to be impaired. If desired the rolling movement can take place on blunt knife edges whereby ice 25 that may accumulate thereon is readily crushed and cleared away.

What I claim is:—

1. A boat davit comprising an outwardly inclined stationary track-way, a boat tackle 30 supporting standard having a curved por-

tion supported on and normally occupying a position adjacent the upper end of the inclined track-way and adapted to roll downwardly thereon, said standard being adapted, subsequent to its rolling movement, 35 to swing outwardly on an axis coinciding with one end of the curved portion thereof, stops arranged to arrest the outward swinging movement of the standard, a boat fall, a windlass having the boat fall attached thereto and secured to a fixed part of the ship, and means adjacent the opposite end of said curved portion for guiding the boat fall during the upward movement of the last mentioned end, the tension of the boat 40 fall acting against the guiding means producing an outwardly directed force against and tending to maintain the standard in outboard position.

2. A boat davit as claimed in claim 1, 50 characterized by the provision of a relatively stationary guideway, and a friction reducing member carried by the first mentioned end of the curved portion of the standard adapted to move along the guideway during the rolling movement of said standard to prevent the latter from sliding over the track-way.

In testimony whereof I affix my signature.
JAN CEELEN.
